ASSIGNORS, BY MESNE ASSIGNMENTS, TO UNITED SHOE MACHINERY CORPORATION,
OF PATERSON, NEW JERSEY, A CORPORATION OF NEW JERSEY.

SHOE-TURNING MACHINE.

1,253,345.

Specification of Letters Patent. Patented Jan. 15, 1918.

Application filed May 18, 1917. Serial No. 169,520.

To all whom it may concern:

Be it known that we, MEYLER BRUNER and WALTER V. NEAL, citizens of the United States, residing at Newton, in the county of Middlesex and Commonwealth of Massachusetts, and Boston, in the county of Suffolk and Commonwealth of Massachusetts, respectively, have invented certain new and useful Improvements in Shoe-Turning Machines; and we do hereby declare the following to be a full, clear, and exact description of the invention, such as will enable others skilled in the art to which it appertains to make and use the same.

15 The present invention relates to turning machines and more particularly to machines for turning the uppers of boots or shoes.

Various types of machines have been devised for turning the heel and forepart of a shoe upper but in operating these machines considerable difficulty has been experienced owing to the liability of damaging the shoe during the turning operation.

It is an object of the present invention to 25 provide a shoe turning machine of an improved type which will properly turn different styles and sizes of shoes while minimizing the liability of tearing the upper, breaking the sole or otherwise damaging the shoe.

30 A feature of the invention contemplates the provision in a shoe turning machine of turning instrumentalities which are actuated pneumatically to perform the turning operation without putting an excessive strain upon the upper or sole of the shoe. A further feature of the invention contemplates the provision of mechanism operating in conjunction with the turning instrumentalities for admitting air under pressure to the interior of the shoe at the completion of the turning operation to distend the upper and lining of the shoe and prevent wrinkling of the latter.

45 A further feature of the invention contemplates the provision in a shoe turning machine of this type of means for holding the shoe to be turned and a member engaging with the toe of the shoe and advanced 50 relative to the shoe holding means to turn the forepart of the shoe by a pressure exerted upon the toe. According to the preferred form of the invention the shoe is held during

the turning operation by an upper support and a sole support.

55

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention, Figure 1 represents a side elevation of the improved turning machine with the supporting member withdrawn into an inoperative position; Fig. 2 is a longitudinal section in elevation of the head of the turning machine shown in Fig. 1 and illustrating the relative 65 positions of the turning instrumentalities with a shoe supported thereon at the commencement of the turning operation; Fig. 3 is a top plan view of the mechanism shown in Fig. 2; and Fig. 4 is a section in elevation 70 of certain portions of the machine illustrating the turning instrumentalities substantially at the completion of the turning operation.

In the illustrated embodiment of the invention the toe of the shoe is engaged by a turning member 10 which is slidably supported within a housing 11, mounted upon a head 12. The shoe is clamped in position against the turning member by a shoe supporting member 15, projecting within the shoe and having an enlarged end 16 arranged to clamp the toe portion of the sole firmly against the turning member 10, as shown clearly in the drawings. The upper of the 80 shoe is supported adjacent the toe by a finger 17 projecting within the upper and secured to a slide 18 guided within a laterally extending frame 19, secured to a head 20.

85 The turning instrumentalities are operated pneumatically to first clamp the toe of the shoe between the turning and supporting members and to next relatively actuate the turning member and finger to turn the upper of the shoe about the finger. To this 90 end the turning member 10 is provided with an elongated stem 25 having a piston 26 secured to the rear end and sliding within a cylinder 27. The piston is normally retained in the position shown in Fig. 2 by a 95 spring 28 surrounding the stem and inter-

posed between the piston and the end of the housing 11. The turning member is actuated to turn the upper of the shoe by admitting air behind the piston 26 and to this end an air pipe 30 is threadedly connected to the end of the cylinder 27 through a coupling member 31. The flow of air is conveniently controlled by a manually operated valve 32 located in the air pipe in a position convenient to the operator. The shoe support 15 is slidingly mounted in the slide 18 and is provided with an enlarged end 33 closely fitting within a tubular extension 34. The extension 34 is threadedly connected with a hollow plunger 35, received within a cylinder 36, threadedly secured to the head 20. The plunger 35 is provided with an axial bore 38 which is smaller than the inner portion of the tubular extension 34 for a purpose to be presently described. Air under pressure is conveniently admitted behind the plunger 35 through an air pipe, indicated at 40 and controlled by a manually operated valve 41. It will be noted that with this construction upon opening the valve 41 pressure is exerted upon the plunger 35 and the piston 33, tending to move both the slide 18 and the support 15 to the left or into the position shown in Fig. 2. Accordingly, in operating the machine the shoe to be turned is first supported upon the member 15 with the upper of the shoe projecting over the finger 17 and the valve 41 is then opened, causing the support and finger to move the shoe into engagement with and clamp the shoe against the end of the turning member 10. Next, the valve 32 is opened admitting air behind the piston 26 which causes the turning member 10 to move to the right against the pressure of the support 15 and finger 17. As this movement of the turning member continues, the support 15 is retracted relative to the finger 17 owing to the greater pressure exerted upon the former and the piston 33 slides within the tubular extension 34. This movement of the turning member and support relative to the finger causes the upper of the shoe to be drawn over the finger, turning the shoe. Owing to the fact that the area of the piston 26 operating the turning member 10 is considerably greater than the area of the end of the plunger 35, the force tending to move the turning member is sufficiently great to overcome the resistance of the support 15 and finger 17 in addition to the resistance incident to turning the shoe, although this force is not sufficiently great to cause damage to the sole or upper of the shoe during the turning operation. It has been stated previously that during the turning operation the support and turning member were moved relative to the finger 17, or in other words, the finger 17 is retracted more slowly than the support 15 to cause the upper of

the shoe to be drawn over the finger. This is owing to the fact that the direct pressure of the turning member 10 is opposed by the support 15 during the turning operation and substantially the only force tending to retract the finger 17 is created by the pull of the upper during the turning operation. It will be noted from an inspection of Fig. 2 of the drawings that pressure upon the end 37 of the plunger 35, tending to resist the withdrawal of the finger, is opposed by the pressure upon the end 39 of the plunger so that the effective resistance to the withdrawal of the finger is governed by the excess of pressure upon the end 37 of the plunger over the pressure on the end 39 of the plunger. This pressure is only sufficient to maintain the upper distended and cause the upper to be drawn smoothly over the turning finger without tending to tear the upper or break the stitches connecting the upper with the sole.

In order to further expedite the turning of the shoe, a pair of spreader members are positioned upon opposite sides of the support 15 and project within the shoe, serving to spread the upper and sole apart. The upper spreader member 43 is arranged to project within the upper of the shoe and is curved to conform generally with the transverse curvature of the upper. This member, as shown clearly in Figs. 2 and 3 of the drawings, is secured to the under side of a plate 44, mounted upon the frame 19 and normally retained in the position shown in Fig. 2 by springs 46, connecting the upturned end 47 of the plate with studs 48, mounted upon the frame. This spreader member is retained in the position shown in Fig. 2 of the drawings until the rearward movement of the slide 18 causes the face of the slide to engage with the lower end of a stud 50, slidingly supported upon the plate, causing the spreader member thereafter to move rearwardly with the slide and finger 17. In order to permit the springs 46 to return the spreader member to its initial position at the completion of the turning operation, the stud 50 is provided with an inclined lower end 51 which engages with a correspondingly inclined face 52, formed upon the frame causing the stud to be elevated against the action of a leaf spring 53 which normally holds the stud in the position shown in Fig. 2. This elevation of the stud releases the spreader member from the slide 18 and permits the return thereof by the springs 46. When the shoe is initially clamped in position the sole is engaged and depressed by a lower spreader member or sole support 55 positioned a slight distance back of the normal position of the upper spreader 43. The lower spreader consists of an L-shaped member 57, arranged to project within the shoe and engage the inner

surface of the sole, secured to the end of a lever 58, pivoted at 59 on the under side of the frame 19. The spreader is normally depressed by a spring 60 interposed between 5 the frame and the lever 58 and the position of the spreader is determined by a stop member 62, engaging with the opposite end of the lever 58 and threaded upon a stud 63, depending from the frame 19. According 10 to this construction, as will be obvious from an inspection of Fig. 4 of the drawings, the continued movement of the turning member 10 forces the support 15 and the finger 17 past the upper and lower spreader members, 15 drawing the upper and sole, respectively, about these members to complete the turning operation. When the rearward movement of the finger 17 causes the slide 18 to engage with the stud 50, the upper spreader 43 is 20 moved rearwardly until it reaches a position substantially opposite the lower spreader at the completion of the turning operation when the elevation of the stud permits the upper spreader to be returned to its initial 25 position. It will be noted that the air pressure behind the piston 33 and plunger 35 serves to clamp the toe of the shoe firmly against the turning member 10 during the entire turning operation. The movement of 30 the turning member 10 is limited by the engagement of the piston 26 with a shoulder 65, formed by the reduced end of the housing 11.

In order to aid in maintaining the upper 35 of the shoe distended prior to and during the turning operation, it will be noted that the elongated stem of the support 15 is provided with an axial bore 66 of restricted size, which permits the air behind the piston 33 40 to leak out into the shoe, causing the pressure within the shoe to be in excess of the pressure without the shoe. In order to distend the upper and maintain the lining free of wrinkles after the turning operation has 45 been completed, provision is made for admitting air within the shoe through the turning member 10. To this end the turning member 10 is provided with an axial bore 67 of restricted size, which is normally closed by 50 a plate valve 68. This valve is secured to a stem 69, sliding within a recess formed in the piston 26 and having an enlarged end 70 which is engaged by a spring 71, received within the recess and normally tending to 55 maintain the valve in the position shown in Fig. 2. In this position the enlarged end 70 extends beyond the face of the piston 26. When the piston reaches the end of the stroke and engages with the shoulder 65, 60 the enlarged end 70 is forced within the recess, as shown clearly in Fig. 4, to open the valve 68 and permit the air within the cylinder to flow through the passage 67 into the toe of the shoe. This serves to smooth 65 out the lining of the shoe and lay it against

the upper, effectually aiding in the completion of the turning operation.

In order to adjust the machine for shoes of different lengths it is necessary, inasmuch as the end of the stroke of the turning member is predetermined, to adjust the initial position of the toe of the shoe at the beginning of the turning operation. To this end the housing 11 is provided with an adjustable cap 75, having a curved shoe supporting end 76 against which the toe of the shoe is clamped by the member 15. The cap is provided with a sliding latch 77, the end of which engages with one of a series of recesses 78 formed in the housing 11 to 75 retain the latch in any adjusted position. The position of the cap 75 determines the initial position of the toe of the shoe and in consequence enables the effective stroke of the turning member to be varied within the 80 desired limits. In addition to this adjustment, the head 12 is slidably supported upon the base of the machine and is provided with a sliding latch 80, arranged to engage with a ratchet plate 81. The latch 90 is conveniently operated through a lever 82 pivoted at 83.

While it is preferred to employ the specific construction and arrangement of parts shown and described, it will be understood 95 that this construction and arrangement is not essential except so far as specified in the claims, and may be changed or modified without departing from the broader features of the invention.

The invention having been described, what is claimed is:

1. A shoe turning machine, having in combination, a turning member arranged to engage with the toe of the shoe, a cooperating member projecting within the shoe and arranged to hold the shoe against the turning member, means for moving the turning member lengthwise of the shoe to turn the upper from the toe toward the heel of the shoe, 110 and an upper support projecting within the shoe to cause the upper to be turned thereover as the toe of the shoe is moved with the turning member.

2. A shoe turning machine, having in combination, a turning member arranged to engage with the toe portion of the shoe, yielding means for holding the toe portion of the shoe in engagement with the turning member, means for actuating the turning member lengthwise of the shoe to turn the latter from the toe toward the heel, and upper supporting means yielding in the direction of the turning operation.

3. A shoe turning machine, having in combination, a turning member adapted to engage with the toe portion of the shoe, a shoe support for yieldingly holding the shoe in engagement with the turning member, mechanism for actuating the turning member 125

- lengthwise of the shoe to turn the latter from the toe toward the heel, and upper and sole supports projecting within the shoe and adapted to support the upper and sole, respectively, during the turning operation.
4. A shoe turning machine, having in combination, a stationary supporting cap, a shoe support adapted to yieldingly clamp the toe portion of the shoe against the cap, a turning member, means for actuating the turning member to cause the latter to engage with the toe of the shoe and move the toe of the shoe in a lengthwise direction toward the heel and an upper support projecting within the shoe and adapted to cause the upper to be turned thereover as the toe of the shoe is moved with the turning member.
5. A shoe turning machine, comprising a shoe support and a coöperating turning member, means for actuating the turning member, and means operative at the completion of the turning operation for forcing air into the interior of the shoe to distend the toe portion of the upper and smooth out the lining.
6. A shoe turning machine, comprising a shoe support, a coöperating turning member adapted to engage with the toe portion of the shoe, means for actuating the turning member in a direction lengthwise of the shoe, and means controlled by the movement of the turning member for forcing air into the interior of the shoe to distend the toe portion of the latter.
7. A shoe turning machine, having in combination, a shoe support, a coöperating turning member, pneumatic means for advancing the shoe support toward the turning member, pneumatic means for actuating the turning member in the opposite direction to turn the shoe, and an upper support about which the upper is turned during the movement of the turning member.
8. A shoe turning machine, having in combination, a turning member, a coöperating shoe support, pneumatic means for advancing the turning member to carry the toe of the shoe toward the heel, pneumatic means for holding the shoe support in engagement with the toe of the shoe during the turning operation, an upper support projecting within the shoe, and means for permitting the upper support to move in the direction of the turning operation.
9. A shoe turning machine, having in combination, a turning member, a coöperating shoe support, a pair of cylinders, a piston supported within each cylinder and connected to the turning member and shoe support, respectively, and means for admitting air under pressure within the cylinders to move the pistons in opposite directions.
10. A shoe turning machine, having in combination, a pair of cylinders, a piston supported within each cylinder, a turning

member connected to one piston, a shoe support connected to the second piston, means for admitting air under pressure within the cylinders to move the shoe support and turning member in opposite directions, and a spring for returning the turning member to initial position when the air pressure is released.

11. A shoe turning machine, having in combination, a cylinder, a piston sliding within the cylinder, a turning member connected to the piston, means for admitting air behind the piston to advance the turning member, a shoe support, and means for actuating the shoe support to cause the latter to yieldingly hold the toe of the shoe against the turning member during the turning operation.

12. A shoe turning machine, having in combination, a housing, a cap adjustably supported upon the housing, a turning member sliding within the housing and cap, means for actuating the turning member, and a shoe support projecting within the shoe and adapted to initially clamp the toe of the shoe against the cap.

13. A shoe turning machine, comprising a turning member, an upper support projecting within the shoe, an upper spreader, means for yieldingly retaining the upper spreader in an advanced position, and means for causing the upper spreader to be moved rearwardly by the upper support during the turning operation.

14. A shoe turning machine, comprising a turning member, means for moving the turning member lengthwise of the shoe to turn the latter, an upper support adapted to move in the direction of the turning movement, an upper spreader, means for causing the upper spreader to move rearwardly with the upper support, and means for returning the upper spreader to initial position at the completion of the turning operation.

15. A shoe turning machine, comprising a turning member having an air passage formed therein, a valve normally closing the air passage, means for actuating the turning member, and means for opening the valve when the turning member completes its stroke at the end of the turning operation to cause air to be directed into the interior of the shoe.

16. A shoe turning machine, having in combination, a shoe support, a stationary cylinder, a piston sliding within the cylinder and connected to the shoe support, a turning member, a second cylinder, a second piston of larger size sliding within the cylinder and connected to the turning member, and means for admitting air under pressure into the two cylinders behind the respective pistons.

17. A shoe turning machine, comprising a shoe support, an upper support, a hollow

stem connected to the upper support, a cylinder within which the stem slides, a piston connected to the shoe support and sliding within the hollow stem to cause the connections for the shoe and upper supports to telescope within one another, and means for admitting air under pressure to the cylinder to advance both the shoe and upper supports.

18. A shoe turning machine, having in combination, means for holding a shoe, a member engaging with the toe of the shoe, and mechanism for advancing the member

relative to the shoe holding means to turn the forepart of the shoe by a pressure exerted upon the toe.

19. A shoe turning machine, having in combination, an upper support, a sole support, a member engaging with the toe of the shoe, and mechanism for advancing the member relative to the supports to turn the forepart of the shoe by a pressure exerted upon the toe.
